EXTRUSION FOR MOUNTING MODULAR UNITS

Irving W. Shell, 442 W. Wellington, Chicago, Ill. 60637

Filed Oct. 16, 1974, Ser. No. 513,899

Term of patent 14 years

Int. Cl. D25—01

U.S. CL. D25—74

FIG. 1

FIG. 2

FIG. 3

FIG. 6

FIG. 1 is an end view of an extrusion for mounting modular units;

FIG. 2 is a fragmentary side view thereof as seen in the direction of lines 2—2 of FIG. 1;

FIG. 3 is a fragmentary side view thereof as seen in the direction of lines 3—3 of FIG. 1;

FIG. 4 is a fragmentary top view thereof as seen in the direction of lines 4—4 of FIG. 1;

FIG. 5 is a fragmentary bottom view thereof as seen in the direction of lines 5—5 of FIG. 1; and

FIG. 6 is a fragmentary perspective thereof.

I claim:

The ornamental design for an extrusion for mounting modular units, as shown.
